Specification for Design.

Patented Feb. 25, 1913.

Application filed December 7, 1912. Serial No. 735,530. Term of patent 14 years.

To all whom it may concern:

Be it known that I, JOSEPH FISCHER, a citizen of the United States, residing at Belleville, in the county of Essex and State of New Jersey, have invented a new, original, and ornamental Design for a Tablet or Similar Article, of which the following is a specification, reference being had to the accompanying drawing, forming part thereof.

The figure is a front view of a tablet showing my new design.

In said figure is shown a design which consists of an elk in bas-relief breaking through a tablet, his antlers surmounted by a clock.

I claim—

The ornamental design for a tablet or similar article, as shown and described.

JOSEPH FISCHER.
